UNITED STATES PATENT OFFICE

1,957,029

PULLEY CONSTRUCTION

Edward F. McKinney, Morris, Ill.

Application October 15, 1932, Serial No. 638,023

3 Claims. (Cl. 16—211)

My invention relates to improvements in pulley constructions of the type used with windows.

In constructing certain types of overhead pulleys for use with windows, it has been the practice heretofore, when by reason of the nature of the pulley's use, the wheel housing could not have an opening in it sufficiently large to permit the wheel to be positioned therein, to cast or otherwise form the housing in two sections, which when assembled, were oppositely positioned with respect to each other and thereby provided a housing split longitudinally and vertically.

The disadvantages of this construction are manifold. In the first place, it is very difficult to form the two sections by standard methods of manufacturing so that the sections when assembled will inter-fit satisfactorily. The completed housing which is made up of the two sections, by reason of this difficulty in manufacturing, has an unfinished and unworkmanlike appearance which is highly undesirable.

Secondly, when the housing is made up of the sections as described, it has been extremely difficult to drill the holes for receiving the shaft on which the pulley wheel is mounted so that the holes will be in alignment in the assembled housing. By reason of the holes being out of alignment, the pulley wheel may be prevented from rotating freely, thereby causing unnecessary friction between the chain and the pulley wheel, with the attendant wearing of the same.

An object of my invention is to overcome the several above-mentioned disadvantages and to provide novel means whereby the wheel may be mounted in the housing without providing a split housing.

Other objects relate to various features of construction and arrangement of parts which will be apparent from a consideration of the following specification and accompanying drawing, wherein

Figure 1 shows two types of pulleys embodying my invention as mounted overhead in a window frame.

Figure 2 is a top plan view of the pulley positioned at the left in Figure 1.

Figure 3 is a top plan view of the other pulley positioned at the right in Figure 1.

Figure 4 is a vertical sectional view taken substantially along the line 4—4 of Figure 1.

Figure 5 is an enlarged detail sectional view taken substantially along the line 5—5 of Figure 1.

Figure 6 is a top plan view of the cover plate portion of my invention.

Figure 7 is an elevational view of a pulley em-

bodying a modified form of my invention, certain portions thereof being broken away and shown in section, and

Figure 8 is a fragmentary end elevation of the pulley shown in Figure 7.

In carrying out my invention I make use of a window frame 11 which comprises in part, side portions 13 and 15 and a lintel portion 17. A window 19 is slidably positioned between the side portions 13 and 15. The above mentioned structure forms no part of my invention and has been described merely for the purpose of clearly disclosing the nature of my invention.

A pulley 21 is associated with the window frame and comprises a pulley housing 23 having a pair of spaced apart side portions 25, a base portion 27, a projecting base portion 29, and an end wall portion 31. The housing is preferably made from cast iron, the side portions, base portion, projecting base portion and end wall portion being integral.

The side portions 25 are provided with aligned openings 33 therein for receiving an axle 35 on which one or more wheels 37, positioned between the side portions, are mounted. Each of the wheels is provided with circumferential recesses 39 for receiving a window cord or chain 41. The axle is provided with head portions 43 for being connected with the side portions.

Means for closing the space between the side portions 25 of the housing, through which the wheel is positioned within the housing, comprises an elongated plate member 45 positioned between the side portions and substantially conforming longitudinally to the peripheral contour of that section of the side portions between which it is disposed.

The plate member is substantially equal in width to the distance between the side portions 25 so that it may fit snugly therebetween.

The plate member 45 has each end portion thereof provided with a pair of laterally extending projecting portions 47 and 49 respectively, which are positioned on opposite sides thereof and oppositely extending with respect to each other.

The projecting portions 47 and 49 extend outwardly from the plate member a distance substantially equal to the thickness of the side portions 25, and are receivable in cut out portions or notches 51 and 53 respectively. The projecting portions 47 and 49 are provided with inclined faces or edges 55 and 57 respectively for engagement with complementary inclined faces or edges 59 and 61 respectively of the notches 51 and 53.

The plate member 45 is further provided with

a pair of laterally extending lug portions 63, which are positioned on opposite sides thereof adjacent the projecting portions 49, and are receivable in recesses 65 in the side portions 25.

- 5 In assembling the pulley, the wheel 37 is first positioned between the side portions 25 of the housing, so that the shaft opening therethrough is in alignment with the openings 33 in the side portions 25.
- 10 The projecting portions 47 of the cover portion 25, are then positioned in the recesses 51 so that the angular portions 67 thereof are positioned in the corresponding angular portions of the notches 51. The projecting portions 49 are then moved into the notches 53. As the projecting portions 49 are moved into the notches 53, the lugs 63 will cause the side portions 25 to be sprung apart, thereby permitting the lugs 63 to move into the recesses 65 with a snap action for connecting the plate member with the side portions.

The pulley wheel 37 is then positioned so that the axle opening therethrough will be aligned with the openings 33 in the side portions. The 25 axle 35 positioned within the aligned openings is provided with head portions 43 which not only connect the axle with the side portions 25, but also prevent the side portions from being sprung apart and thereby securely locking the plate member with the side portions.

30 The pulley 69 shown in Figure 1 is a different style of pulley embodying my invention, but as all of the salient features of the pulley 69 correspond to those described in connection with the pulley 21, the reference characters are made common to both pulleys.

The pulleys are adapted for being connected with the window frame in the manner shown in Figure 1.

- 40 In Figure 7 I have illustrated a modified form of my invention. In this form of the invention, the cover plate 71 is preferably of uniform width throughout its length, which width is substantially the distance between the side plates 73. The 45 projecting portions 47 and 49 and the lugs 63 are dispensed with and in lieu thereof the end portions of the cover plate are provided with threaded openings 75 therein for receiving screws 77 which extend through openings in the side portions 73 for connecting the cover plate 71 with the side portions.

45 The cover plate 71 is shown as being provided with an extending or cord guide portion 79 having an opening 81 therethrough, through which a chain or cord, extending over the pulley from another pulley, may extend. The cord guide portion 79 is adapted for confining and prevent-

ing a chain or cord positioned above the pulley, from whipping and striking the pulley and thereby creating a noise.

50 It will be noted that the cover plate, particularly when it has a guide portion associated therewith, may be made of a different material from that of which the pulley housing is constructed. When the housing is made of cast iron, the cover plate and guide portion may be made of brass, thereby reducing to a minimum any noise resulting from the chain or cord engaging the guide portion or cover plate.

55 While I have illustrated and described the preferred embodiment of my invention, it will be understood that various modifications and changes 90 may be made without departing from the spirit or scope of the invention.

I claim:

55 1. A pulley comprising a housing provided with a pair of spaced apart walls, a wheel therebetween supported by the same, the upper portions of said walls extending above said wheels, a closure plate for said wall portions having laterally extending ends adapted to engage the edges of said wall portions and an intermediate section adapted to 100 be disposed between said walls, and cooperating lugs and sockets in said plate and wall portions adapted to be pressed into engagement with a snap action for detachably holding said plate in position.

2. A pulley comprising a housing having a pair of spaced walls for supporting a wheel therebetween and having portions extending beyond the periphery of said wheel, said wall portions having a pair of opposed notches in the edges thereof, a 110 detachable cover plate for said wall portions having a pair of lateral extensions adjacent one end thereof pivotally receivable within said notches, and cooperating means on the edges of said plate adjacent the other end thereof and on the inner 115 faces of said wall portions for retaining said cover in position.

3. A pulley comprising a housing having a pair of spaced walls for supporting a wheel therebetween and having portions extending beyond the 120 periphery of said wheel, said wall portions having a pair of opposed notches in the edges thereof, a detachable cover plate for said wall portions having a pair of lateral extensions adjacent one end thereof pivotally receivable within said notches, 125 and cooperating means on the edges of said plate adjacent the other end thereof and on the inner faces of said wall portions for retaining said cover in position, said means comprising a pair of lugs and a pair of sockets for receiving the same with 130 a snap action.

EDWARD F. MCKINNEY.
